UNITED STATES PATENT OFFICE.

ALBERTIS HEWITT, OF PITMAN, NEW JERSEY, ASSIGNOR TO VICTOR TALKING MACHINE COMPANY, A CORPORATION OF NEW JERSEY.

COMBINED MECHANICAL AND ELECTRICAL REPRODUCER AND TRANSMITTER.

Original application filed December 15, 1924, Serial No. 756,571. Divided and this application filed February 19, 1925. Serial No. 10,335.

This invention relates to the reproduction and transmission of sound, and more particularly to means adapted for use in combination with talking machines, or electrical circuits, or both, for reproducing recorded sounds, for converting electrical impulses into sound waves, and for converting sound waves into electrical impulses.

An object of the present invention is to provide an improved sound box or reproducer for mechanically reproducing talking machine records.

Another object of the invention is to provide an improved combination device for either mechanical or electrical reproduction, or both, of talking machine records.

Another object is to provide an improved device capable of performing the above functions, and capable of being used as a magnetic transmitter or microphone.

A further object of the invention is to provide an improved device of the above character which may be employed, in combination with other elements, as a radio loud speaker.

A still further object is to provide novel means capable of producing superior results for mounting the stylus bar. These and other objects will be apparent from the following detailed description.

Stated broadly the invention comprises improved means for mechanically reproducing talking machine records, for electrically reproducing talking machine records, for simultaneously reproducing such records mechanically and electrically, and one which is adapted for use as an electrical transmitter or microphone, and as a loud speaker unit for radio receiving systems.

The invention is capable of receiving a variety of mechanical expressions, one of which is illustrated in the accompanying drawings, but it is to be expressly understood that the drawings are for purposes of illustration only and are not designed as a definition of the limits of the invention, reference being had to the appended claims for this purpose.

In the drawings,

Fig. 1 is a front elevation illustrating one embodiment of the present invention;

Fig. 2 is a sectional side elevation taken on the line 2—2 of Fig. 1;

Fig. 3 is a longitudinal sectional view taken on the line 3—3 of Fig. 1;

Fig. 4 is a detail perspective view illustrating one type of stylus bar which may be employed;

Figs. 5 and 6 are sectional details of the stylus bar and its mounting, Fig. 6 being taken on the line 6—6 of Fig. 5;

Fig. 7 is a diagrammatic view illustrating one manner in which the device of the present invention may be employed for mechanically and electrically reproducing sound;

Fig. 8 is a side elevation illustrating the device adapted for use as an electrical transmitter or microphone; and

Fig. 9 illustrates diagrammatically, one manner in which the device may be used as a radio loud speaker.

Referring to the drawings wherein like reference characters refer to like parts throughout the several views, 10 is a shell or casing of any suitable form and material that is bent inwardly at its forward face to form a circular shoulder 11. A cup 12, of any suitable material, such as aluminum, and provided with a central opening 12^a, is maintained in engagement with shoulder 11 in any desired way, as by means of screws 13. In contact with the inner periphery of the shell 10, is a cylindrical member 14 that is preferably formed of a dielectric, such as vulcanized rubber. Secured to the opposite or rear end of the chamber formed by the member 14, as by means of screws 15, is an annular member or ring 16 provided on the inner face thereof with an inwardly projecting shoulder 16^a. In engagement with the inner periphery of member 16 and bearing against shoulder 16^a, is a resilient ring 17, which is preferably formed of rubber, for a purpose to be described hereinafter. Secured to the rear face of member 16, as by means of screws 18, is a closure member 19 provided with a central flanged portion or neck 19^a surrounding an opening 19^b.

Any suitable electro-magnetic means may be mounted in the chamber formed by the elements 12, 14 and 19 described above for converting mechanical vibrations into electrical vibrations. In the form shown, this means comprises a permanent, circular magnet 20 which is divided at one side to provide

spaced poles 20^a that are located at the opposite sides of the medial plane of the magnet. Secured to the inner surface of each pole 20^a, as by means of screws 21, are 5 U-shaped pole pieces 22 which extend radially inward from the pole and which are mounted so that the limbs of one project toward the corresponding limbs of the other pole piece. A flattened spool 23, provided at its opposite ends with flanges 23^a, is positioned between the limbs of pole pieces 22 and a suitable coil of wire 24 is wound around the spool between its flanges. Extending within the spool 23 and centrally 10 thereof, is a flat plate 25 constituting an armature, which is secured at its upper end in any suitable manner, as by means of brazing, to a horizontally disposed flexible member or wire 26 that is attached at its 15 forward end to a stylus bar 27, the rear end of the flexible rod or wire 26 being fixedly secured to a flexible diaphragm 28 which is resiliently and securely supported by the resilient member 17 previously referred to. 20 Disk 28 may be formed of any suitable material but preferably mica is employed. The particular shape or form of the disk and the manner in which it is constructed and mounted forms no part of the present 25 invention.

Any suitable means may be employed for mounting the stylus bar in operative relation to the casing 10. The present invention, however, includes a novel mounting 30 which is productive of superior results. In the form shown, a bar 29 extends horizontally across the front face of casing 10 adjacent the lower portion thereof, and is preferably formed integral with said casing. 35 Secured in any desired manner to the front face of bar 29, is a knife edge 30 which extends parallel with the axis of the bar 29 and at right angles to the axis of the stylus bar 27. Mounted on the front face of bar 40 29, in planes parallel to the axis of the stylus bar 27 and equi-distant therefrom, are a pair of T-shaped lugs 31 (see Figs. 1 and 6) which receive and retain in cooperative position a pair of U-shaped springs 32 which are 45 suitably secured, as by means of brazing, to the opposite sides of the stylus bar 27 in the plane of the knife edge 30. Lugs 31, springs 32, and knife edge 30, are so proportioned that the springs are maintained in flexed 50 condition, as is clearly illustrated in Fig. 5, when the stylus bar is engaged with the knife edge 30 and the springs 32 have their U-shaped ends engaged under the lugs 31. The usual needle or stylus 33 and retaining 55 means 34 are provided at the lower end of the stylus bar.

Suitable means are preferably provided for dampening the natural vibrations of the stylus bar and also for preventing whipping 60 of the same. In the form shown, this means

comprises a rubber tube 35 which surrounds the stylus bar and extends from the armature 25 outwardly and downwardly to the upper edges of springs 32.

Secured to the cup 12 and extending 70 within the circular magnet 20 are binding posts 36 to which are secured the opposite ends of coil 24. Conductors 37, which are attached in any convenient manner to the binding posts 36, pass through an opening 75 12^b in the cup 12, to a suitable circuit (Fig. 7) for receiving the electrical impulses generated by vibration of the armature 25.

The neck or flanged portion 19^a of the disk 19 constitutes means for securing the combination device to the tone-arm 38 (see Figs. 80 7 and 9) of a talking machine. This arm 38 may be mounted in any suitable manner adjacent a turn table 39 which is adapted to carry the usual record tablet 40. 85

As illustrated in Figs. 3 and 8, the device of the present invention is adapted for use as an electrical transmitter or microphone. When so employed, a bushing or sleeve 41 is inserted within the neck 19^a, and a mouth-piece 42 of any suitable type is removably 90 secured to the bushing 41.

When the device is used as a mechanical reproducer, the rotation of sound record tablet 40 vibrates the stylus 33, stylus bar 27, and diaphragm 28, in a manner well known in the art. The dampening means 35 reduces irregularities of sound and materially assists in the clear reproduction of the sound record 40. If it is desired to employ the device as a combination mechanical and electrical reproducer, the conductors 37 are connected with a suitable electric circuit, such as is illustrated in Fig. 7 for example. The vibrations of the stylus bar are not 100 only imparted to the diaphragm 28 to mechanically reproduce the records, but said vibrations are also effective to vibrate the armature 25, thereby inducing electrical 105 effects or currents of variable E. M. F. in the coil 24 and consequently in the electrical circuit connected with the conductors 37. 110

When employed as a microphone, the device is supported in any suitable manner and the sounds to be transmitted are directed 115 into the mouthpiece 42 whereupon the vibrations thus imparted to diaphragm 28 result in vibration of the armature 25 and generation of the currents of variable E. M. F. in the coil 22. This current is transferred by 120 the conductors 37, to any suitable electrical circuit.

If it is desired to employ the combination device of the present invention as a radio 125 loud speaker, the conductors 37 are connected with the output or plate circuit of a suitable radio receiving system (not shown) and the casing 10 is positioned in operative relation with a suitable horn in a manner such as that diagrammatically illustrated in Fig. 9, 130.

wherein the casing is mounted on the goose-neck of a talking machine. The variable currents in conductors 37 and consequently in the coil 24, cause the armature 25 to be 5 vibrated. These vibrations are transmitted by the flexible portion 26 of the stylus bar to the diaphragm 28 and the sound waves so produced are amplified by the horn of the talking machine.

10 It will thus be seen that there is provided a combination device, capable of producing superior results, which may be employed as an electrical or mechanical reproducer, or both, as an electrical transmitter or microphone, and as a loud speaker. Novel and effective means are also provided for mounting the stylus bar. The parts are readily assembled and so constructed that distortion is reduced to a minimum. The device may 15 be quickly changed from association with certain elements, where it is adapted to perform one or more of the above enumerated functions, and operatively connected to other elements to perform the other functions enumerated.

20 While the embodiments of the invention illustrated in the drawings have been described with considerable particularity, it is to be expressly understood that the invention is not limited thereto, since the same is capable of being embodied or carried out in a variety of ways, some of which will now readily suggest themselves to those skilled in the art, while changes may be made in the details of construction and arrangement without departing from the spirit 25 of the invention. Reference is therefore to be had to the claims hereto appended for a definition of the limits of the invention.

What is claimed is:

- 40 1. In combination, a casing, a diaphragm in the casing, a knife-edge carried by the casing, a stylus bar engaging said knife-edge and secured to said diaphragm, U-shaped springs carried by said bar and means normally flexing said springs for retaining said bar on the knife-edge.
- 45 2. In combination, a casing, a resiliently mounted diaphragm in the casing, a knife-edge on said casing, a stylus bar engaging said knife-edge and secured to said dia-

phragm. U-shaped springs carried by said bar, means normally flexing said springs for retaining said bar on the knife-edge and yielding means surrounding said bar for dampening the vibrations thereof.

55

3. A stylus bar mounting comprising, in combination with a casing, a bar on said casing, a pair of T-shaped lugs carried by said bar, a knife-edge carried by the bar intermediate said lugs, a stylus bar in engagement with said knife-edge, and a pair of U-shaped springs carried by said bar and having engagement with said lugs for maintaining said bar in operative position.

60

4. A stylus bar mounting comprising, in combination with a casing, a pair of retaining lugs carried by said casing, a knife-edge carried by said casing, a stylus bar having operative engagement with said knife-edge, and U-shaped springs carried by said bar 70 and having engagement with said lugs for maintaining said bar in operative position.

65

5. In combination, a casing, a pair of T-shaped lugs carried thereby, a stylus bar, and a pair of U-shaped springs secured to 75 said bar and engaging said lugs for maintaining said bar in operative position.

70

6. A stylus bar mounting comprising, in combination with a casing, a knife-edge carried by said casing, a stylus bar having 80 engagement with said knife-edge, U-shaped springs carried by said bar, and means co-acting with said springs for retaining said bar on the knife-edge.

75

7. In combination, a casing, a knife-edge carried thereby, a stylus bar engaging said knife-edge, U-shaped springs carried by said bar, and means normally flexing said springs for retaining said bar on the knife-edge.

80

8. In combination, a casing, a stylus bar 90 mounted for oscillation on said casing, U-shaped springs carried by said bar and extending substantially parallel to the plane of the axis of said bar and to the axis of oscillation, and means co-acting with said 95 springs for retaining said stylus bar in position.

90

In testimony whereof I have signed this specification.

ALBERTIS HEWITT.
